SANDER DRUM

Arnett L. Thorson and Louis C. Nolte, Chicago, Ill.

Application June 3, 1949, Serial No. 97,046

7 Claims. (Cl. 51—194)

This invention relates generally to sanding machines and more particularly to an improved power-driven floor sander.

Although the sanding machine disclosed which embodies this invention is intended primarily for use in finishing floors, many of the novel features of the invention incorporated therein may be used in other types of sanding machines such as the hand models used in finishing furniture, walls, boats, etc., and stationary sanders where the work is moved over the sander.

In sanding floors it is essential that the sandpaper be frequently replaced during the sanding operation, not only to substitute new sheets for those which have had the abrasive surface worn off or caked with varnish and the like, but also to change the grade of sandpaper from coarser grades for initial sanding to finer grades for the finishing operation. Although other types are used, the general practice is to mount the sheets on the cylindrical surface of a rotatable drum. To do this, the usual practice has been to provide rectangular sheets of sandpaper which are wrapped around the drum and secured thereto by a clamp-lock device generally comprising a bar or bars of metal extending the length of the drum and functioning as cams or clamps engaging the ends of the sandpaper sheet. The ends are tucked radially inwardly underneath or between the bars and the bars rotated or screwed down. Other arrangements have been provided in which the sandpaper is held in place by various clamping devices which draw the paper tight while locking pressure is applied, but none of these has proved wholly satisfactory in that either the paper does not pull down evenly or becomes askew, or the paper is not securely clamped when installed, and creeps loose. In any event, the best of conventional clamps should extend parallel with the drum axis, but such permits the drum to bounce and mar the floor each time the drum rotates. Clamps arranged helically to avoid this bounce encounter other difficulties of adjustment or use. Much trouble is also encountered by unskilled users not being able to understand the operation of the sandpaper securing devices because they cannot see or understand how they operate. Misuse or carelessness results.

Another difficulty encountered resides in certain characteristics of the sandpaper itself. Sandpaper is likely to become wrinkled or the abrasive surface broken during installation on the drum, thereby producing an irregularity which mars the surface of the floor or introduces a tear in the paper as the drum rotates.

Most of the conventional locking devices require tool access at the ends of the drum if multiplicity of adjustments is to be eliminated. This interferes with compactness and transmission drives and requires an arrangement of parts which prevents sanding close to baseboards.

Accordingly, one of the main objects of this invention is to provide a novel, improved arrangement for attaching the sandpaper to the sanding drum by which the sheets may be rapidly changed on the job without the need for special tools or for access to the face ends of the drum,

2

and the manner of attachment to the drum is readily apparent to anyone.

A further object is to provide an arrangement whereby the sheets are securely supported on the surface of the drum in such fashion that they cannot become wrinkled, and are self-adjusting and self-tightening during operation, automatically and otherwise.

Another object is to provide an improved form of abrasive sheet, particularly adapted for attachment to the drum of a sander, which is less likely to wrinkle or tear than conventional sheets.

A further object of the invention is to provide a sheet and drum structural arrangement which eliminates all marring of the floor and which will sand to within fractions of an inch of the wall board.

Various other objects and advantages of this invention will present themselves to those familiar with the art on reading the following specification in conjunction with the appended claims and the drawings, in which:

Fig. 1 is a plan view showing a sanding drum for a sanding machine incorporating a preferred embodiment of the invention;

Fig. 2 is a section of the drum taken on line 3—3 of Fig. 1;

Fig. 3 is a section taken on line 4—4 of Fig. 2; and

Fig. 4 is a plan view of the sandpaper sheet embodying features of the invention.

By sandpaper, as used herein and in the claims, is meant any sheet material having abrasive particles or a polishing medium carried by a flexible backing such as cloth, paper, skin, sheet material, etc., and includes emery cloth, carborundum paper, and polishers such as felt, wool, and flocculated fibers.

At the front end of the member 18 a cover 20 is attached by a pair of hinges 21 and curved to follow the contour of the side plates. This cover may be swung upwardly to expose the drum 11 in front so that the sandpaper 22 may be readily mounted or removed.

The arrangement by which the novel abrasive sheets 22 are attached to the drum 11 is shown. The drum comprises a pair of circular end plates 70 and 71 which are welded to the ends of a hollow cylinder 72. The end plate 71 projects beyond the end of the cylinder 72 and has the drive pulley 33 formed integrally therewith. The other end plate 70 is flat-sided and flush with the end of the cylinder 72 so that the sanding surface extends substantially to the inside edge of the side plate, permitting sanding quite closely to walls, eliminating the need for hand finishing the marginal edges of floors.

The outer surface of the cylinder 72 has a sheet of rubber 73 cemented thereto which covers the entire surface except for a small triangular inclined recess 74 at the center thereof. Substantially, at the center of the inclined wall of the triangular recess, a button or hook 75 is provided which projects radially a slight distance from the surface of the inclined wall but not high enough to extend to the surface of the rubber 73. On each end of the drum 11 an inclined slot 76 is provided which extends through the rubber 73 and through the end of the cylinder 72. The two slots 76 are located in line with each other and are circumferentially spaced from the hook 75.

The abrasive sheet 22 has the shape shown, being cut to a point at one end and having a mating swallow-tail form at the other. A grommet 77 preferably is provided at the pointed end of the sheet 22. To install the sheet 22 on the drum 11, the grommet 77 is slipped over the hook 75, and the drum 11 is rotated to wrap the sheet 22 around it. The two trailing ends or tips 78 of the sheet 22 are then slipped into the slots 76, assuming the position shown in Fig. 8.

After insertion with the cylinder stationary, the two tips 78 are held lightly in the slots 76 by the action of a pair of centrifugal weight elements 80 pressed outwardly

by springs 81. The pressure of the springs 81 is such that the elements 80 are urged outwardly with a slight force, the force being just great enough to hold the ends 78 of the sheet 22 against inadvertent dislodgement and yet permit them to be readily slipped sidewise or withdrawn simply by finger pressure on the strip 22.

The centrifugal weights 80 are pivotally attached to the end plates 70 and 71 by pins 82. The plates 70 and 71 are relieved to provide spaces as indicated at 83 and 84 to receive the members 80 on one side, while the spaces 84 on the opposite side compensating for the weight reduction effected by the presence of the spaces 83.

As has been stated, when the drum is stationary the trailing ends 78 of the sheet may be readily removed from the slots 76. However, when the drum starts up, the friction of the sandpaper on the floor stretches and adjusts the sandpaper in place with the trailing tips pushed deeper into the slots 76. Then as the drum gains speed and is rotated at high speed, centrifugal force causes weights 80 to be forced outwardly, clamping the trailing ends 78 securely in place.

Many advantages result from this arrangement. In the first place, it is practically impossible manually to install the sandpaper 22 incorrectly so as to cause bulges or wrinkles. No tools are needed, and once the operator has hooked the grommet 77 over the hook 75 and inserted the two tips 78 in the slots 76, the job is completed. Even though the sandpaper 22 may be loose on the drum 11, the initial rotation of the drum as the motor is started automatically causes the paper 22 to locate itself correctly and hug the surface of the drum 11, forcing the tips 78 all the way into the slots 76. Since the strip 22 is suspended from a single central point 75, it is bound to roll onto the drum without wrinkling and the hugging action during the acceleration flattens the paper against the drum. The hugging action comes into play immediately after the drum starts to rotate, but the centrifugal force of the weights 80 is not great enough to prevent motion of the ends 78 into the slots 76 until higher speeds are reached. Stopping the drum releases the centrifugal force and the sandpaper can be removed by one's fingers only.

The springs 81 may be dispensed with, but it is preferred to use them for they hold the ends 78 lightly in place while the drum 11 is stationary.

The shape of the leading edge of the strip 22 is complementary to the shape of the trailing edge. This results in two advantages. First, the strips 22 may be cut from a roll of material or large sheet without waste, and a much greater percentage of the abrasive surface of each sheet is brought into contact with the floor than heretofore possible with conventional machines. Second, the leading and trailing edges of the strip 22 substantially meet when the strip is wound around the drum 11, covering the drum completely without overlapping. The strips 22 are preferably made such length that only sufficient clearance is left to compensate for manufacturing tolerances. The leading and trailing edges need not be cut on straight lines as long as they are respectively converging and diverging, following the same contour, and do not overlap when wound around the drum 11. However, it is desirable that the strips 22 be symmetrical and supported at a central point, for otherwise they tend to move to the side of the drum 11 as it rotates, and there are no abrupt edges to cause chatter marks on the floor being sanded.

From the foregoing it will be seen that a very superior arrangement for removably securing abrasive sheets to the drum has been provided. The sheets are inexpensive to fabricate and extremely simple to remove and apply. Furthermore, it is practically impossible to install a sheet improperly so that it may wrinkle or tear.

The first step is to install the proper grade of sandpaper on the drum 11 for the task at hand. The old sheet 22 is removed by withdrawing the trailing ends 78

from the slots 76 and rotating the drum 11 until the hook 75 is accessible so that the leading end of the sheet 22 may be unhooked. The new sheet 22 is then hooked on the hook 75, and the drum is rotated in the drive direction, wrapping the sheet around the drum until the slots 76 are accessible. The trailing ends 78 are then inserted in the slots 76. Anytime the machine is stopped, it can be tilted back to take the weight off of the drum.

It is preferred to have the drum lightly engaging the floor when the motor 13 is started. The sandpaper immediately tightens and adjusts itself in correct position and, as the motor comes up to speed, the machine is moved back and forth over the floor.

From the foregoing description it will be apparent that a greatly improved sander has been provided which is rugged in construction, easy to operate, and simple to maintain in adjustment. It will also be appreciated that the design may be modified and adapted to other types of sanders than the particular model described.

Accordingly, various changes and modifications such as will present themselves to those familiar with the art may be made without departing from the spirit of this invention whose scope is defined by the following claims.

What is claimed is:

25. 1. In combination, a rotatable drum and a sheet of sandpaper having a sanding face and back side wrapped around the drum with the sanding face disposed outwardly, one end of the sandpaper being pointed and the other end being swallowtailed to have two trailing tips, means on the pointed end of said sheet for attaching same to the drum, a pair of slots in the surface of said drum for receiving the tips of the other end with the sanding face engaging a rigid surface on the drum, and centrifugal means including an element lightly contacting the back side of said tips at said rigid surfaces to accommodate relative movement between the sheet and drum during slow rotation of the drum and clamping said tips rigidly in place when said drum is rotated at sanding speeds.
30. 2. In combination, a rotatable drum and a sheet of sandpaper wrapped around the drum, one end of the sandpaper being swallowtailed to have two trailing tips, a pair of slots in the surface of said drum for receiving the tips, and centrifugal means including elements lightly engaging the back side of said tips to press them outwardly against a portion of the drum and to accommodate relative movement between the sheet and drum during the initial rotation of the drum at its starting point and said element clamping said tips rigidly in place when said drum is operating at full speed when said drum is rotated.
35. 3. In a sander, a rotatable drum, means on said drum midway between the ends thereof for supporting one end of a piece of sandpaper, a pair of slots in the surface of the drum circumferentially spaced from said supporting means, and means associated with said slots for clamping the trailing end of the sandpaper strip, said means including centrifugally responsive elements engaging said trailing end on the back face thereof in relative sliding relationship under an increasing clamping force with increased speeds of said drum, and resilient members urging said elements into light engagement with said trailing end under resting conditions of said drum.
40. 4. In a sander, a rotatable drum, means on said drum midway between the ends thereof for supporting one end of a piece of sandpaper, said sandpaper being free to move axially along said means, a pair of slots in the surface of the drum circumferentially spaced from said supporting means and adjacent the ends of the drum, centrifugal means associated with said slots and engaging the back side of said sandpaper in relative sliding relationship for clamping the trailing end of the sandpaper sheet at working speeds of said drum and means for lightly holding said centrifugal means in place subject to said freedom of movement under resting conditions of the drum.
45. 5. In a sander utilizing a flexible sheet of abrasive ma-

terial having a leading and a trailing edge, a cylinder rotatable about a fixed axis, means for pivotally securing the leading edge to the surface of the cylinder midway along the axis of rotation thereof, and means secured to the cylinder for clamping the trailing edge to the cylinder, said clamping means including resilient elements lightly engaging the back side of the trailing edge under resting conditions of the cylinder, and centrifugally influenced elements urged into clamping relationship with the trailing edge of the sheet in response to a predetermined centrifugal force whereby the flexible sheet is rigidly clamped as the drum revolves at such speed as to apply a predetermined centrifugal force.

6. In a sander utilizing a flexible sheet of abrasive material having a leading edge and a bifurcated trailing edge, a hollow cylinder rotatable about a fixed axis, means secured to an outer surface of the cylinder for fastening the leading edge of the sheet to the cylinder at its axial midpoint, said cylinder having a pair of slots therein adjacent the periphery of the cylinder, said slots being adapted to receive the ends of the bifurcated trailing edge, a pair of centrifugally responsive arms pivotally mounted at one end within the cylinder, the free end of each of said arms being adjacent one of the slots to engage comparatively lightly in relative sliding relationship the end of the trailing edge extending therethrough under resting conditions of the cylinder, and means for rotating the cylinder to produce a centrifugal force to rotate the arms outwardly whereby the arms clamp the ends against the under surface of the cylinder 30 after a predetermined speed is attained.

7. In a sander utilizing a flexible sheet of abrasive material a pointed leading edge and a trailing edge with a pair of spaced tips, a rotatable cylinder having an indented portion and a pair of slots therein, said indented portion being located in the surface of the cylinder midway along the axis of rotation, means secured in said indented portion for fastening the pointed edge to the cylinder, said slots being located directly opposite each other on the outer periphery of the cylinder, and means responsive to centrifugal force mounted within the cylinder adjacent each of the slots including elements lightly holding the trailing tips in place under resting conditions of the cylinder, said elements rigidly clamping the trailing tips of the sheet in place upon the cylinder reaching a predetermined rotational speed.
